UNITED STATES PATENT OFFICE.

GEORGE H. MORRIS, OF LONDON, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

BUTTON.

1,268,868.

Specification of Letters Patent. Patented June 11, 1918.

Application filed July 13, 1914. Serial No. 850,743.

To all whom it may concern:

Be it known that I, GEORGE H. MORRIS, a subject of the King of England, residing at London, in the county of Kent, England, have invented certain Improvements in Buttons, of which the following description, in connection with the accompanying drawings, is a specification, like reference characters on the drawings indicating like parts 10 in the several figures.

The present invention relates to improvements in buttons formed from a single piece metallic blank and its object is to provide a button which may be easily and cheaply 15 constructed leaving only a small amount of waste and which shall possess a maximum amount of strength for the metal which it contains. The invention also includes within its scope the novel blank herein shown 20 as utilized in the construction of the button. It has been found that a button comprising a head formed of two layers of sheet material of which the under layer comprises two parts connected by an eye possesses the 25 advantages above mentioned in addition to others. For example, with little or no modification the metallic blank may be utilized in the construction of an enameled or japanned button or a button having a covering of celluloid or other plastic coating.

As herein shown the head of the button is provided with a portion overlying and covering the line of division between the two parts which comprises the under portion 35 of the head. The overlying portion may be flattened or made convex in accordance with the shape desired in the finished button and it may be of such dimensions compared with the lower part of the head 40 as to form a retaining shoulder for the plastic covering material.

Another feature of the invention relates to the eye of the button and consists in swaging or otherwise beveling the sheet metal stock from which the eye is formed so that it will present a curved edge over which the attaching thread is drawn, so that the latter will not be cut, and also curved edges adjacent to the head, so that the edges of the buttonhole will not be frayed.

These and other features and advantages of the invention will be best understood and appreciated from the following description of preferred embodiments thereof selected

for purposes of illustration and shown in 55 the accompanying drawings, in which,—

Figure 1 is a plan of a blank according to the present invention;

Fig. 2 is a sectional view of a button formed of the blank shown in Fig. 1; 60

Fig. 3 is a section on the line 3—3 of Fig. 1;

Fig. 4 is a plan of a modified form of blank;

Fig. 5 is a sectional view of a complete 65 button embodying the blank shown in Fig. 4;

Fig. 6 is a modified form of the complete blank shown in Fig. 5.

The blank shown in Fig. 1 comprises two 70 semi-circular portions A and A¹, the straight sides of which are joined by a bar or connector A². The semi-circular portion A¹ has projecting from the middle of the semi-circular part of its periphery a short connecting piece B having at its outer end a disk B¹. The blank is formed by stamping or pressing from a sheet of brass or other suitable material and the pressing or stamping dies are preferably so formed that the 80 connector A² will be somewhat hollowed at its middle as shown in Fig. 3, in order that the eye of the button which is formed from this connector will have a rounded or beveled edge and will therefore be less liable to 85 cut the thread by which the button is affixed. Adjacent to its ends the connector A² is rounded in an opposite sense so that the outer edges of the eye will present a smooth and rounded surface which will not fray the 90 buttonhole.

The blank having been formed is bent so that the two straight edges of the semi-circular portions A and A¹ lie close together, to form the base of the head of the button, 95 the connector A² being bent in such a way as to form the eye thereof. The short connecting piece B and the disk B¹ are then doubled over the semi-circular portions A and A¹ as shown in Fig. 2 so as to form 100 a neat button.

The head thus formed may then be covered with celluloid, leather or other suitable material or it may if desired be merely enameled. The disk B¹ may be "dished" in 105 stamping so that it is more readily formed into the dome-shaped head shown in Fig. 2.

According to the modified construction

shown in Figs. 4, 5 and 6 the semi-circular portions A and A¹, the connector A² and the connecting piece B are similar to the corresponding portions shown in Fig. 1. The disk B² is, however, of smaller diameter than the semi-circular portions A and A¹ so that when bent over as shown in Fig. 5 it lies within the edge of these portions. In this way the button when covered may be readily given a beveled edge. Further, if the disk B² is "dished" during the process of stamping the head of the button may be more easily made convex as shown in Fig. 6 and the convexity will be the more pronounced owing to the fact that the disk is of smaller diameter than the semi-circular portions.

It will be noted by referring to Figs. 5 and 6 that a substantially complete circular shoulder is formed adjacent to the edge of the head on account of the difference in diameter of the overlying portion B² and the underlying portions A and A¹. This shoulder serves as an anchorage for securing the plastic covering in place. The plastic covering in turn serves as means for permanently maintaining the two parts of the head in contact with each other and positively prevents their separation.

It will therefore be seen that according to the present invention a button of substantially the usual shape may be made from a single piece metallic blank in a rapid and easy manner and that the same may be covered in the usual way with celluloid, or the like, or if made according to Figs. 1 and 2 may be merely enameled or coated in a like manner.

Having thus described my invention, I claim as new and desire to secure by Letters Patent of the United States:

1. A metal button comprising a head having a covering part with a circular periphery, an under part comprising two semi-circular sections disposed with straight edges abutting, and an eye connected at either end to one section and having a convex outer surface adjacent to the sections

and a concave outer surface remote from said section.

2. A button comprising a head formed of two layers of sheet material, the under layer comprising two parts connected only by an eye integral therewith and formed from the sheet of which the parts are formed.

3. A button comprising a head formed of two layers of sheet material, the under layer comprising two semi-circular parts disposed with their straight sides adjacent to each other, and an eye merging at each end into one of the semi-circular parts at its straight side.

4. A button comprising an eye, each side of which merges into a flat part disposed at right angles to the plane of the eye and forming a part of the head said parts being otherwise unconnected at adjacent edges, and a single head-forming part overlying both of said flat parts, said flat parts, eye, and head-forming part being formed from a single piece of sheet material.

5. A button having a head comprising two layers of sheet material integrally connected at one edge and folded flatwise upon each other, and a plastic covering molded over the edges of both layers.

6. A button having a head comprising curved superimposed layers of sheet material of different diameters integrally connected at one edge, and a plastic covering.

7. A button blank having two head parts connected by a narrow strip of sheet material, said strip having its center portion concaved and its end portions concaved.

8. A button having a sheet metal head and a sheet metal eye with its edges swaged outwardly at the curve of the eye and inwardly adjacent to the head.

In testimony whereof I have signed my name to this specification in the presence of two subscribing witnesses.

GEORGE H. MORRIS.
